UNITED STATES PATENT OFFICE.

JIM B. FULLER, OF CLAREMONT, NEW HAMPSHIRE, ASSIGNOR TO HIMSELF AND JAMES P. UPHAM, OF SAME PLACE.

IMPROVED APPARATUS FOR SEPARATING FIBERS OF FLAX, HEMP, &c.

Specification forming part of Letters Patent No. 41,812, dated March 1, 1864.

To all whom it may concern:

Be it known that I, JIM B. FULLER, of Claremont, in the county of Sullivan and State of New Hampshire, have invented, made, and applied to use a certain new and useful Improvement in Means for Separating Fibers for Paper-Stock, &c.; and I do hereby declare the following to be a full, clear, and exact description of the said invention, reference being had to the annexed drawings, making part of this specification, wherein—

Figure 1 is a vertical section of my improved apparatus, and Fig. 2 is a plan of the same.

Similar marks of reference denote the same parts.

Vegetable materials—such as straw, wood, &c.—have heretofore been separated and reduced by the action of heat and water and by a grinding operation, as may be seen in Letters Patent granted to me November 17, 1863. Such vegetable materials have also been cured in a closed vessel by heat and pressure. This, however, involved the necessity of separate charges introduced in such vessels, and precluded the use of a continuous operation, and no provision was made for subjecting the material to a second curing operation in case the first was insufficient.

The nature of my said invention consists, first, in a means for supplying the straw or other vegetable material to the curing-vessel without lessening the steam-pressure employed in such vessel, whereby a constant curing operation under pressure can be performed; second, in passing such cured material in a regulated quantity from the curing-vessel into and through the grinding apparatus by means of a pump and weighted regulator that insures uniformity in the supply to the grinder; and, third, in applying superheated steam to the cured material immediately before it passes to the grinder, whereby the silicious materials are more thoroughly softened and dissolved, so as to pass away with the water employed.

In the drawings, *a* is a curing-vessel, of suitable size and shape, to which steam or hot water is supplied by suitable pipes in the necessary quantity.

b represents the steam-pipe.

The top *c* of the vessel *a* is fitted with a feeding-slide, *d*, formed with a cylinder, *c'*,

upon said slide, and this is below a fixed plate, *e*, carrying a hopper, *f*.

g is a lever by which the cylinder *c'* and slide *d* can be moved.

The hopper *f* is not over the opening *h* in the head *c*, and hence when under this hopper *f* the cylinder *c'*, will fill with the straw or other material, and the slide *d* will close the opening *h*; but when the cylinder and slide are moved (by *g*) the cylinder is brought over *h*, and its contents drop out into the curing-vessel, and the plate *e*, covering the upper end of the cylinder *c'*, prevents the escape of steam from the curing-vessel, and on the reverse movement the cylinder *c'*, is again brought beneath the hopper. In its passage, however, I relieve the pressure of steam in the cylinder *c'* by a small hole or pipe at *i*.

A shaft, *k*, passing into the curing-vessel, forms the fulcrum of the lever *g*, and at the lower end of this shaft an arm, *l*, is provided, that prevents the vegetable material becoming packed at the entrance to the pipe *m*, and thereby obstructing the same.

The pipe *m* leads to the pump *n*, and thence to the second curing-vessel, *o*, where superheated steam is supplied through perforations beneath a jacket, *p*, and acts in said vessel *o* to complete the curing operation, by softening all silicious materials previous to the grinding operation.

q is my grinder, that may be of any desired character, rotated by a belt or otherwise to the pulley *r*.

s is a pipe leading back from the grinder to the upper part of the curing-vessel *a*, so that the material may be circulated through the apparatus more than once, if desired; or a cock may be provided at the lower end of the pipe *s* for drawing off the cured material, or said cured material may be drawn away by the pipe *t* at the lower part of *a*.

The pump *n* is to be worked by suitable mechanism, and should have valves fitted to slide or turn, and also worked automatically, and the regulator *u*, adjoining the pump, is formed as a cylinder, with a weighted plunger that rises when the pump is operative, and keeps up the supply to the grinder by its descent, while the return or filling movement of the pump takes place.

The curing-vessel *o*, in which superheated

steam is applied, may be varied in shape so long as the object desired is attained—namely, of completing the softening operation by the superheated steam in the passage of the vegetable material from the first curing-vessel to the grinder, in order that the said material may reach the grinder in the best condition for its separation into stock for paper, &c.

What I claim, and desire to secure by Letters Patent, is—

1. The cylinder *c'* and slide *d*, in combination with the hopper *f* and opening *h*, for supplying the vegetable material to the curing-vessel and maintaining the pressure in said vessel, as specified.

2. The arm *l* and revolving shaft *k*, applied to the curing-vessel *a*, for the purposes and as specified.

3. Regulating the amount of material pass-

ing from the curing-vessel to the grinder by a pump, applied between said grinder and curing-vessel, as specified.

4. The plunger *u*, in combination with the pump *n*, for the purposes and as specified.

5. The curing vessel *o*, applied between the curing-vessel *a* and the grinder *q*, whereby superheated steam is applied to the material before grinding, for the purposes set forth.

6. The return-pipe *s*, connecting from the bottom of the grinder to the upper portion of the curing-vessel, for returning the ground material to the curing-vessel, for the purposes and as specified.

Dated December 26, 1863.

JIM B. FULLER.
